(57) **CLAIM**

The ornamental design for an audio component face, as shown and described.

DESCRIPTION

FIG. 1 is a front elevational view of an audio component face showing our new design; and,

FIG. 2 is a top plan view thereof, the bottom plan view being a mirror image thereof.

The broken line showing of the rectangular region in the claimed area on FIG. 1 and the broken line showing on FIG. 2 is for illustrative purposes only and forms no part of the claimed design.

1 Claim, 1 Drawing Sheet

FIG. 1

FIG. 2
